RESONANT CHAMBER FOR ACCORDIONS

Alfredo Frontalini, Numana, Italy

Application October 1, 1948, Serial No. 52,339
In Italy March 6, 1948

20 Claims. (Cl. 84—376)

1

The present invention relates generally to air-pressure-operated musical reed instruments, such as accordions, and particularly to resonant means for improving the tone quality and for augmenting the tone volume of such instruments and for reflecting sound from such instruments to without thereof.

The usual construction of accordions comprises two relatively fixed compartments, in one of which the treble reed elements are housed, while the base reed elements are located in the other fixed compartment. Connecting the two fixed compartments is an expandable compartment or bellows which supplies the necessary air under pressure to operate the several reed elements. Very little thought has been given to improving the tone quality and the volume of heretofore known instruments of this kind.

The general purpose of the present invention is to incorporate long overdue refinements in accordions to the end of enhancing their tone quality as well as their volume of sound emanating from the air-pressure-operated reed elements, whereby an overall improvement in the sound effects of such instruments is achieved. The means whereby such overall improvement in sound effects is accomplished are relatively simple. They comprise substantially resonant chambers of fixed volumes composed of what may be termed resonant exterior chamber portions and resonant interior or sound reflecting members.

The exterior portions are substantially oblong and have finely executed walls, the interior faces of which are smooth. The walls are curved so that the exterior open ends of the chamber portions are substantially smaller than their interior ends. Arranged in proper correlation with these exterior chamber portions are relatively thin walled, smooth faced, highly resonant interior chamber portions, to be known as sound reflecting members. The latter comprise substantially oblong, continuous, relatively deeply dished and also finely executed structures with smoothly finished walls. All corners and the edges at their open ends are curved. These sound reflecting members partly surround and are spaced from the reed blocks supporting the reeds, and are also uniformly spaced from the walls of the exterior chamber portions located in the fixed compartments. In these latter compartments are arranged partitions or boards forming reed block supporting members to which the reed blocks are fixedly secured. These portions have a plurality of valve-controlled openings.

2

The resonant sound reflecting members are detachably and freely or floatingly and resiliently suspended in correct relation in respect to the exterior chamber portions by suitable resilient elements extending from the reed block supporting members. These suspending elements are so arranged that they hold the sound reflecting members at the desired uniform spacing from the walls of the fixed chamber portions. The edges at the open ends of the sound reflecting members are substantially parallel with at least some portions of the walls of the fixed chamber portions and, due to their floating suspension, are substantially free and are capable to respond unrestrictedly to sound vibrations.

As stated, in one of the fixed compartments of the instrument there are located reed blocks carrying the treble reeds. These reeds are operated from an exterior keyboard, while the base reeds mounted in the other fixed compartment are operated by means of another keyboard. The supporting member for the base reed blocks divides the fixed compartment into a relatively deep outer and a relatively shallow interior portion, whereas the supporting member for the treble reed blocks forms so-to-speak an outer wall of the compartment housing these reed blocks.

The peripheral spacing between the reflector members and the fixed chamber portions in each of the fixed compartments is designed to permit free passage of air when the expandable compartment is either expanded or contracted.

Having thus described generally the structural arrangement of the present invention, its principal object is the provision of combination sound chambers having fixed volumes, one for the treble reeds and another for the base reeds, whereby the sound waves emanating from the air-pressure-operated reeds are first directed inwards through resonant, gradually inwardly enlarging exterior chamber portions, whereupon they are reflected in outward direction by means of resonant, deeply dished, outwardly flared reflector members, whereby the tone quality of the instrument is greatly improved and the sound volume is materially increased.

A further object of this invention is to provide resonant, smooth faced, continuous, relatively thin walled sound reflecting means partly enclosing the sound producing elements of an accordion operated by air pressure, and which sound reflecting means are adapted to readily respond to sound vibrations produced by said elements. A further object of the present invention is to provide in an accordion type instrument hav-

ing pressure operated sound producing elements associated with the fixed compartments of the instrument, thin walled, resonant, smooth faced, continuous sound reflecting means with rounded corners and edges so disposed within the instrument that their open ends are directed outwardly in respect to the instrument body, and which sound reflecting means are floatingly suspended so that their whole bodies freely and unrestrictedly respond to sound vibrations produced by the sound producing elements of the instrument and direct sound emanating from said elements in outward directions.

A further object of this invention is to provide for the aforesaid sound reflecting means, suitable suspension means which facilitate substantially free movement of said sound reflecting means so that they unrestrictedly respond to sound vibrations produced by the sound producing elements of the instrument.

The foregoing and still further objects and important advantages of this invention will become more fully apparent from the ensuing description, in conjunction with the accompanying drawings, wherein:

Fig. 1 represents a typical transverse cross section through the instrument of the present invention;

Fig. 2 is a section taken on line 2—2 of Fig. 1 with portions of one of the sound reflecting members broken off and with the expansible member removed;

Fig. 3 is a fragmental section taken on line 3—3 through Fig. 2;

Fig. 4 is a partial interior view of the sound reflecting member for the treble reeds;

Fig. 5 is a partial top view thereof;

Fig. 6 is a section taken on line 6—6 of Fig. 4; and

Fig. 7 is a fragmental, enlarged section taken on line 7—7 of Fig. 1 illustrating the base reed sound reflecting member.

Referring now more specifically to the figures, numeral 10 denotes one of the fixed compartments of an accordion for housing the treble reeds and which compartment has an extension 11 supporting a keyboard 11' for operating valves controlling the operation of the treble reeds. Numeral 12 indicates the other fixed compartment of the instrument which houses the base reeds, and numeral 13 denotes the expansible compartment or bellow section of the accordion. Fixed compartment 12 is provided with a keyboard 12' for actuating valves controlling the operation of the base reeds.

As is well known, an accordion is played by the manual expansion and compression of bellows 13, whereby air is forced into the instrument and expelled therefrom, respectively, while simultaneously the various keys of the keyboards are depressed and released to open and close suitable valves which control the passage of air through the vibratory reed elements supported in reed blocks. Again referring to Fig. 1, keyboard 11' is composed of a plurality of keys 14 and 15 connected by means of a system of levers 16 to the different valves 17 which control openings 17' forming passages through reed block support 18 to the several treble reed blocks 19. These reed blocks are diagrammatically shown in plan view in Fig. 2. Reed block supporting member 18 extends between the four walls of fixed compartment 10 and forms a closure for a resonant chamber indicated at 20, reference to which will be had presently.

Fixed compartment 12 of the instrument is also provided with a reed block support 21 which extends to all four walls of the compartment and is provided with apertures 22 controlled by valves 23 operated by means of a lever arrangement 24 by way of the keys of keyboard 12'. Supported by member 21 are base reed blocks 25 and 26. Reed blocks 25 extend partly into bellows 13 while reed block 26 is much lower.

The aforesaid description of the arrangement of reed blocks, the outer fixed compartments 10 and 12 and bellows 13 is common to most accordions structures. In heretofore produced instruments of that type very little attention has been devoted to the quality of their acoustic properties, consequently these properties may not be generally considered ideal from the point of view of sound, resonance, value and volume. The present invention is intended to improve these acoustic properties by the employment of specially designed resonant chambers or sound boxes which include resonant sound receiving and sound propagating or sound reflecting members. In fixed compartment 10 there is arranged the already-mentioned chamber or sound box 20 composed of an outer chamber portion 21, the walls of which are curved from the interior end of compartment 10 towards the exterior end, which latter end terminates at supporting member 18. That sound chamber portion resembles substantially an inverted funnel with the smaller end directed outwardly. The walls of the chamber portion 21 are relatively thin, having finely executed smooth surfaces, which gradually curve. All corners of chamber portion 21 are carefully rounded, as shown in Fig. 2 at 28.

Within the larger end of chamber portion 27 there is located a sound reflector 29. This reflector comprises a relatively deeply dished, substantially oblong, thin-walled structure, the surfaces of which are carefully finished and the corners and the connections between the flanges and the bottom being smoothly rounded, as indicated at 30 and 31 in Figs. 2, 4, 1, 3 and 6. Also the outer edges of the sound reflector are rounded as indicated at 32. This sound reflector is held removably in position at its short sides by means of spring clips 33 and 34 which are perforated to receive the heads of screws 35 extending from the reflector body and which clips are attached to angles 36 and 37 supported by posts 38 and 39, respectively. The suspension of the sound reflector is so designed as to assure the reflector's responding freely and fully to any sound vibration. Reflector 29 partly encloses reed blocks 19 and is spaced from these blocks by suitable spacer buttons 40, clearly seen in Figs. 1, 2 and 3. The rounded edges of reflector 29 are also spaced peripherally from the walls of chamber portion 27, preferably by means of suitable spacer buttons 41 shown in Figs. 1 and 2. The circumferential edges of sound reflector 29 are substantially parallel with the corresponding wall parts of chamber portion 27 so that the spacing between these two instrumentalities is uniform throughout.

In fixed compartment 12 a sound chamber is formed by the walls of that compartment, the interior surfaces of which are also carefully executed to a fine smoothness, and wherever curvatures occur, such as in the bodies of the walls indicated at 42 and 43 in Fig. 1, as well as at the corners of the compartment, these curvatures are produced with great care so as to eliminate any undue obstruction to the free passage of sound.

Reed blocks 25 and a portion of reed block 26 are partly enclosed by a sound reflector 44, which latter comprises a thin-walled, deeply dished structure having smooth surfaces and carefully rounded corners 45. Edge 46 at the open end of the reflector is also rounded. Reflector 44 is suspended within resilient clips 46, shown in Fig. 7, by means of screws 47 passing through the clips. These clips are attached to angles 48 supported by posts 49. These posts extend from and are secured to reed block support 21. The suspension of reflector 44 by means of resilient clips 46 assures a free response of the reflector body to sound vibrations. It will be noted that the outer opening of fixed compartment 12 is of a much lesser area than the interior end of that compartment, and that the rounded outer edge portions 46 of reflector 44 are substantially parallel with the interior surfaces of compartment 12.

It is being emphasized that both reflector members 29 and 44, as well as their corresponding chamber portions in their respective fixed compartments 10 and 12 are highly resonant, and that they readily respond to sound vibrations emanating from the vibratory reed elements when the latter are subject to air under pressure by the action of bellows 13.

Operation

When the instrument is played by the repeated expansion and compression of the bellows and the operation of the keys, the vibratory reed elements are caused to produce sound waves. These sound waves are conveyed first towards the interior of the instrument through the inwardly funneled outer sound chamber portions. These inwardly propagated sound waves are now reflected by resonant reflectors 29 and 44 and are directed by them outwardly. The spacing between the sound reflectors and the outer chamber portions permits the free passage of air into and out of the instrument. The fact that both the outer chamber portions as well as the reflectors are so arranged as to readily respond to the sound vibrations induced by the air-actuated reeds, not only the tonal quality of the instrument is improved, but also the volume of the emitted sounds is substantially increased, whereby the overall tonal efficiency of the instrument is materially improved over those produced by existing similar instruments.

Structure

The attachment and suspension of sound reflectors 29 and 44, while shown in their presently preferred form, may be altered, depending upon the material used for these instrumentalities, but in any event their suspension and position must be such that a free passage of air is assured between their walls and those of the outer chamber portions and that they readily respond to sound vibrations. The material from which the outer chamber portions and the reflectors are constructed is subject to considerable variations, depending upon the type and size of instrument in which they are to be used, but are preferably made of either suitable wood, plastic, metals and alloys of the lightness and thickness necessary to produce the desired sound and volume effects required. As may be observed, the combined outer chamber portions and the corresponding sound reflectors are constructed in a manner similar to that of sound boxes employed in string instruments.

Sound chambers

The tone quality of musical instruments depends largely upon the correct response of their structure to the sound vibrations produced. The effectiveness of such response is considerably enhanced in many instruments by the employment of resonant sound chambers or sound boxes, provided that the latter are designed correctly for the entire desired range of sound vibration frequencies to be used. One of the important factors governing the resonancy of the sound chamber, which resonancy in turn controls the tone quality of the instrument, is the volume of such sound chambers.

For high frequency sound vibrations, sound chambers of relatively small volume are employed, such as for instance for a violin, whereas instruments producing sound vibrations of a lower frequency or lower pitch must have a much larger volume, such as used in the base violin.

Inasmuch as the average pitch range of the treble reed elements located in one of the fixed accordion compartments of the present invention is materially higher than the pitch range of the base reed elements, housed in the other fixed compartment, the sound chamber for the treble reeds will be of a substantially lesser volume than the sound chamber for the base reeds. Thus it becomes quite obvious that the volumes of these two respective chambers are fixed for their different ranges of sound vibration frequencies.

Conclusion

While in the foregoing specific structures of the present device were described and discussed, these structures are subject to considerable variations as and for the reasons already indicated. Therefore such changes, variations and improvements are to be considered to reside within the scope of the present invention, as defined by the annexed claims.

I claim:

1. The combination with an air-pressure-operated musical instrument having sound-producing elements responsive to air under pressure passing through them, of solid-bodied, continuous, resonant sound reflecting means freely suspended in rear of and spaced from said elements and, due to their free suspension, being adapted to respond to the sound vibrations and to reflect and convey sound produced by said elements in outward direction.

2. In an air pressure-operated musical instrument having sound-producing elements operative by air under pressure, resonant, smooth-faced, continuous sound reflecting means freely suspended about, spaced from and partly enclosing said elements and being capable of freely responding to sound vibrations produced by said elements and being further adapted to reflect sound and to convey and direct outwardly reflected sound produced by said elements.

3. In an air pressure-operated musical instrument having compartments of fixed and variable volumes, sound-producing elements in the compartment of fixed volume responsive to air under pressure produced by the operation of the compartment of variable volume, substantially dish-shaped relatively thin-walled, smooth-faced, resonant, continuous and self-contained sound-reflecting means partly surrounding and being spaced from said elements, suspension means for said sound-reflecting means adapted to facilitate unrestricted vibration of the latter means induced by sound emanating from said elements, said

sound-reflecting means being positioned to convey sound produced by said elements in outward direction.

4. In an air pressure-operated musical instrument having sound-producing elements operative by air under pressure, a dished, resonant, continuous, self-contained sound-reflecting member so suspended about and spaced from said elements that it will convey sound produced by the latter in outward direction, and suspension means for said member facilitating the latter's bodily, unrestricted response to sound vibrations.

5. In an air pressure-operated musical instrument as per claim 4, said member being of a fixed volume.

6. In an air pressure-operated musical instrument as per claim 4, said member comprising a relatively thin-walled structure, the body and the peripheral edges of which are substantially free.

7. In a musical instrument, at least two sets of keyboard-operated vibratory sound-producing elements responsive to air under pressure, two relatively rigid compartments of fixed volumes; an operative, expansible compartment of variable volume detachably connecting the rigid compartments; each of the rigid compartments having outwardly directed, smooth resonant walls; sound-reflecting, relatively thin-walled, resonant, dished members spaced from the walls of said rigid compartments and surrounding substantial parts of but being spaced from said elements, the open ends of said members being free to vibrate and being directed outwardly.

8. In a musical instrument as per claim 7, said sound-reflecting members having curved interior and exterior surfaces at their inner ends and curved edges, the latter being substantially in parallelism with corresponding edges of the rigid compartments.

9. In a musical instrument as per claim 7, said sound-reflecting members being not only spaced from said elements in all directions, but also peripherally from the walls of said rigid compartments.

10. The combination with an accordion structure of the type indicated, of a dished, freely suspended resonant sound reflector spaced from and surrounding with its dished walls the sound-producing elements of the accordion and being adapted to not only convey sound from such elements in outward direction, but to bodily respond to sound vibrations.

11. In an accordion having two fixed compartments provided with perforated supporting members and an expansible compartment connecting said fixed compartments, keyboard-operated vibratory treble and base elements, arranged in blocks, the blocks of the treble elements associated with one of the supporting members, the blocks of the base elements being secured to the other supporting member and partly extending into the expansible compartment, said fixed compartments being substantially oblong and having outwardly curving, smooth-surfaced walls and curved corners; resonant, relatively thin-walled and relatively deeply dished, substantially oblong, round-cornered sound reflecting members of fixed volumes partly surrounding and being spaced from said treble and base blocks, and being freely suspended within and thus being spaced from the walls of said fixed compartments, the walls of said reflecting members being directed outwardly.

12. In an accordion, as per claim 11, the edges of the open ends of said reflecting members being substantially parallel with at least some portions of the walls of the fixed compartments.

13. In an accordion, as per claim 11, the edges of the open ends of said reflecting members being substantially parallel with at least some portions of the walls of the fixed compartments, the open ends of said reflecting members being substantially distanced from said supporting members for the reed blocks.

14. In an accordion, as per claim 11, the edges of the open ends of said reflecting members being substantially parallel with at least some portions of the walls of the fixed compartments, the open ends of said reflecting members being substantially distanced from said supporting members for the reed blocks, and resilient supporting elements for said reflecting members detachably engaging the latter.

15. The combination with an accordion, of a resonant sound chamber having therewithin a dished, freely suspended, resonant sound reflector.

16. The combination with an accordion, of resonant sound chambers, one for the treble reeds and another for the base reeds, both chambers having freely suspended, dished, bodily resonant sound reflectors, the free walls of which being directed outwardly.

17. The combination with an accordion, of resonant sound chambers, one for the treble reeds and another for the base reeds and wherein the sound chambers comprise exterior and interior portions, the latter forming dished sound reflecting structures freely suspended within said exterior portions and having their free open wall edges directed outwardly of the accordion.

18. The combination with an accordion, of resonant sound chambers for the treble and the base reeds, said chambers being of fixed volumes and including as one of their parts removably and freely mounted, dished sound reflectors.

19. The combination with an accordion, of resonant sound chambers for the treble and the base reeds, said chambers being of fixed volumes and including as one of their interior parts removably freely mounted sound reflectors, the latter comprising dished structures with their free open end edges directed outwardly.

20. The combination with an accordion, of resonant sound chambers, one for the treble reeds, another for the base reeds, each chamber being of a fixed volume and comprising outer chamber portions and inner, removably and resiliently mounted dished sound reflectors spaced from said outer chamber portions and having their free open wall edges directed outwardly.
